UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CONVERTIBLE GENERAL-SERVICE BALLAST-CAR.

1,164,918.

Specification of Letters Patent. Patented Dec. 21, 1915.

Application filed June 10, 1915. Serial No. 33,238.

To all whom it may concern:

Be it known that I, ARGYLE CAMPBELL, a citizen of the United States, residing at Chicago, in the county of Cook and State of Illinois, have invented a certain new and useful Improvement in Convertible General-Service Ballast-Cars, of which the following is a full, clear, concise, and exact description, reference being had to the accompanying drawings, forming a part of this specification.

This invention relates to improvements in convertible general service ballast cars and is in the nature of an improvement on the construction shown in my prior Patent 1054089 of February 25, 1913.

The object of the invention is to provide a car adapted either for general service or ballast use wherein the side dump floor doors are adapted to be unhinged and disposed so as to form the bottoms of the hoppers.

Another object of the invention is to provide a car of the type above indicated wherein is employed door operating mechanism including a plurality of links and so arranged that in the closed position of the doors, torsional strains on the shafts are eliminated.

The invention furthermore consists in the improvements in the parts and devices, and in the novel combinations of the parts and devices herein shown, described and claimed.

In the drawing forming a part of this specification, Figure 1 is a side elevation of half a car showing my improvements in connection therewith. Fig. 2 is a longitudinal central sectional view of the structure illustrated in Fig. 1, but showing the opposite end of the car, and Fig. 3 is an enlarged transverse vertical sectional view of the car, the left-hand portion of said figure showing the position of the parts when the car is adapted for side dumping and the left-hand portion of said figure showing the position of the parts when the car is being utilized as a center dump hopper or ballast car.

In said drawing, the car body is shown as provided with end walls 10, side walls 11, having inwardly inclined lower portions 12, side stakes 13, diagonal braces 14 and center sills 15. The car is shown as provided with a hopper section intermediate the trucks, the hoppers being formed by transversely extending diaphragms 16 and end,

triangular shaped hopper sheets 17-17. Over the tops of the channels forming the center sills extends longitudinally of the car an A-shaped sheet 18 to the top of which is secured a longitudinally extending floor plate 19. At the ends of the car, in the construction which I have shown, the floor section 20 is permanent and when the car is being used for ballast service, temporary end walls composed of boards may be inserted in the grooves 21-21 formed therefor on the inside of the car in line with the stakes at the ends of the hopper section. When the full length of the car is being utilized, the temporary end wall boards may be stored in similar grooves 22 at the ends of the car.

Over the hopper section, the floor of the car is formed by a plurality of side dump floor doors 23, one for each hopper, said doors 23 being detachably hinged at their inner edges as indicated at 24. Each of the doors 23 extends out slightly beyond the lower edges of the side walls and is also provided with a pair of outwardly and downwardly inclined arms or brackets 25.

Extending lengthwise of the car, on each side thereof, and within the space provided between the side stakes, tops of the diaphragm and inclined lower portions of the side walls, are operating shafts 26-26. The shafts are rotatably mounted in suitable bearings attached to bracing plates 126 secured to the stakes, side walls and diaphragms. The shafts 26 have mounted thereon a plurality of hubs or drums 27 corresponding in number to the number of arms or brackets 25 on the hinged floor doors. Extending between each of said drums 27 and its corresponding arm or bracket 25, is a link connection consisting of four pivotally connected links 28, 29, 30, 31 and a hook shaped link 32, the pivotal connection between the latter and the link 31 being directly above the shaft 26. At its lower end, the hook shaped link 32 is normally pivotally connected by its corresponding arm or bracket 25 as indicated at 33, the latter pivotal connection being detachable for a purpose hereinafter specified.

Each of the shafts 26 is operated in any suitable or well-known manner, and I have indicated conventionally at 34 in Fig. 1 such a means.

Each of the hoppers of the car is provided with a center dump hinged door 35, the

doors 35 being hinged along their upper edges beneath the channels of the center sill. Each set of doors 35 on the opposite sides of the central line of the car is operated from a longitudinally extending shaft 36 mounted in suitable bearing brackets 37 secured to plates or sheets depending from and attached to the diaphragm 16. On each shaft 36 is a plurality of hubs 38, between which 5 and the doors is a pivotally mounted short link 39 and hook shaped link 40, the latter being pivotally connected to its corresponding door and to the short link 37, the pivotal connection between the two links being 10 so disposed that a line drawn therefrom to the pivotal connection between the hook 40 and the door will pass either through the center of the shaft or below the latter to thereby relieve the shaft from torsional 15 strain when the doors are closed and overcome any tendency of the shaft to rotate when load is on the doors. The shafts 36—36 are preferably simultaneously operated by means of a transverse shaft 40 (see 20 Fig. 1), the latter having suitable worm and gear connections with each of the shafts 36 located at the end of the hopper section, but which I have not deemed it necessary to show since this construction is well known. 25 A suitable ratchet device 41 is provided at the end of the shaft 40, the same being illustrated conventionally. Extending lengthwise of the car at the bottoms of the series of hoppers on each side of the center line are 30 braces or supports which, in the form shown, each comprises a Z bar 42 and an angle 43, it being understood that the Z bars and angles are secured together and in turn are secured to the end hopper sheets 17—17. 35 40 When the car is used for carrying material in bulk, the doors 23 are retained in the position shown in full lines on the left-hand side of Fig. 3. For side dumping the doors are retained in the same position and 45 may be let down to dump the load by rotating the operating shaft 26, the open position of the doors 23 being indicated by dotted lines on the left-hand side of Fig. 3. When the car is being utilized for carrying ballast 50 or as a center dump hopper, the doors 23 are unhinged from the hinge butts 44, and their inner edges are then pinned or bolted to brackets 45—45 at the bottoms of the hoppers. At the same time, the arms 25 of each 55 door are detached from their pivotal connections at 33 with the hook-shaped links 32 and are connected with the hook shaped links 32 at a higher point as indicated at 46. By this means I am enabled to sustain the 60 load on the doors 23 in this position directly beneath the operating shafts 26 so that when the doors 23 form the bottoms of the hoppers there is still no tendency for the shafts 26 to be rotated. As will be understood, by providing a worm and worm gear 65

connection between the transverse operating shaft 40 and the shafts 36, the doors 35 may be held in any adjusted open position to thereby regulate the streams of ballast from the car as the latter is moved along the 70 track.

Although I have herein shown and described what I now consider the preferred embodiment of my improvement, yet I am aware that changes and modifications may be made in the details of construction and arrangement of parts without departing from the spirit of the invention and I contemplate all such changes and modifications as come within the scope of the claims appended hereto.

I claim:

1. In a car of the character described, the combination with a car body provided with a hopper section and having hinged center dump, hopper doors, of a plurality of hinged side dump floor doors, the latter being adapted to be unhinged and positioned so as to form the bottoms of the hoppers, operating shafts for said side dump doors, drums 35 on said shafts, flexible connections between each drum and side dump door each including a hook shaped link arranged to rest on the shaft to thereby relieve the shaft from torsion, and longitudinally extending braces 40 at the bottoms of the hoppers.

2. In a car of the character described, the combination with a car body provided with a hopper section and having hinged, center dump hopper doors, of a plurality of hinged, side dump doors, the latter being detachably hinged to the car and adapted to be positioned to form the bottoms of the hoppers, operating shafts for said center dump hopper doors, connections between 105 said shafts and center dump hopper doors including hook shaped links adapted to take over the shafts and thus eliminate tendency of the shaft to be rotated when load is on the doors, and longitudinally extending 110 braces at the bottoms of the hoppers and secured to the end hopper sheets.

3. In a car of the character described the combination with a car body provided with a hopper section, of a plurality of members, 115 corresponding in number to the number of hoppers and adapted to serve interchangeably as floor portions of the car extending from the center sill to the sides thereof or as downwardly and inwardly inclined bottoms 120 of the hoppers, devices for detachably supporting said members along their inner edges when the same form portions of the floor, and adjustable length connections for supporting said members at their outer 125 edges, the required length of said connections varying in accordance with the position occupied by said members.

4. In a car of the character described, the combination with a car body and provided 130

with a hopper section having hinged, center dump hopper doors, of a plurality of side dump floor doors located over the hopper section of the car, said floor doors being detachably hinged along their inner edges, and when unhinged adapted to form bottoms of the hoppers, operating shafts for said floor doors, laterally extended brackets from the outer edges of said doors, and adjustable 10 length link connections between said brackets and said shafts.

5. In a car of the character described, the combination with a car body provided with a hopper section and having hinged, center dump hopper doors, of a plurality of detachably hinged side dump floor doors the

latter being adapted to form the bottoms of the hoppers, operating shafts for said floor doors, variable length link connections between said floor doors and said shafts, operating shafts for said hopper doors, and flexible connections between said hopper doors and said hopper door shafts including pivotally connected members some of which are of hook shape and adapted to rest upon the 20 25 shafts.

In witness that I claim the foregoing I have hereunto subscribed my name this 6th day of May, 1915.

ARGYLE CAMPBELL.

Witness:

JOSEPH HARRIS.
